Primary Examiner—Paula A. Greene

(74) Attorney, Agent, or Firm—Caesar, Rivise, Bernstein, Cohen & Pokotilow, Ltd.

(57) **CLAIM**

The ornamental design for the trim for a handle, as shown and described.

DESCRIPTION

FIG. 1 is a top plan view of trim for a handle showing my new design;

FIG. 2 is a bottom plan view thereof;

FIG. 3 is a side elevational view thereof, the opposite side is a mirror image; and,

FIG. 4 is an end elevational view, the opposite end is a mirror image.

The dashed lines shown in the figures represent environmental subject matter and form no part of the claimed design.
